UNITED STATES PATENT OFFICE

ROBERT C. RUSSELL, OF DALLAS, TEXAS

DESIGN FOR AN AUTOMOBILE RADIATOR BAR

Application filed August 28, 1930. Serial No. 36,815. Term of patent 7 years.

To all whom it may concern:

Be it known that I, ROBERT C. RUSSELL, a citizen of the United States, residing at Dallas, in the county of Dallas and State of Texas, have invented a new, original, and ornamental Design for Automobile Radiator Bars, of which the following is a specification, reference being had to the accompanying drawings, forming part thereof.

Fig. 1 is a front elevation of an automobile

radiator bar embodying my new design, and Fig. 2 is a side edge elevation of Fig. 1.

The bar is attached vertically to the front of the automobile radiator centrally of the sides thereof and is affixed to the top and bottom portions of the radiator.

I claim:

The ornamental design for an automobile radiator bar, as shown and described.

ROBERT C. RUSSELL.
